UNITED STATES PATENT OFFICE.

GORDON LEE, OF EASTON, PENNSYLVANIA, ASSIGNOR TO INGERSOLL-RAND COMPANY, OF JERSEY CITY, NEW JERSEY, A CORPORATION OF NEW JERSEY.

ROCK DRILL.

Application filed April 16, 1926. Serial No. 102,486.

This invention relates to rock drills, but more particularly to a pressure fluid controlling device for fluid actuated rock drills of the hand held type.

5 The objects of the invention are to enable the pressure fluid controlling means to be actuated in an improved and simplified manner and to render the guiding handle of the rock drill strong and durable.

10 Other objects will be in part obvious and in part pointed out hereinafter.

The invention consists of the combination of elements and arrangement of parts having the general mode of operation substantially as hereinafter described and more particularly pointed out in the appended claims and illustrated in the accompanying drawings, in which

Figure 1 is an elevation, in section, of a 20 rock drill of the hand held type equipped with a controlling means constructed in accordance with the practice of the invention,

Figure 2 is a view of one of the grip portions, partly in section, illustrating one of 25 the positions which the handle sleeve may assume in practice, and

Figure 3 is a view similar to Figure 2 illustrating the position of the handle sleeve when the valve is fully open.

30 Referring to the drawings, the invention is shown embodied in a rock drill of the hand held type in which a cylinder A is provided with a free exhaust port B. Within the cylinder A is arranged a reciprocating hammer piston C having a rearwardly reduced extension D reciprocable in a bore E formed in the rearward portion of the cylinder A.

A back head F forms a closure for the 40 rearward end of the cylinder and the forward end of the cylinder is sealed in this instance by means of a front cylinder washer G interposed between the front end of the cylinder and a front head H. In addition to forming a closure for the front end of the cylinder A, the washer G also acts as a guide for an anvil block J adapted to transmit the blows of the piston C to a drill steel K supported by the front head H.

45 60 The parts comprising the casing of the rock drill, namely, the cylinder A, the back head F, the front head H, and the front cylinder washer G may be held or clamped in operative position with respect to each other

in any suitable manner, preferably by means 55 of the usual side bolts, (not shown).

Pressure fluid for actuating the percussive element of the rock drill may be conveyed from a source of supply through a conduit L secured to the back head F by means of 60 a suitable connection O. Such pressure fluid may pass to the rearward end of the bore E through a passage P.

The piston C illustrated in the drawings is of the type which may be constantly exposed to pressure fluid at the rearward end of the extension D. In this instance the extension D constitutes the means for distributing the pressure fluid to the ends of the cylinder A. Accordingly, a passage Q 70 leading from the rearward portion of the bore E communicates at its front end with the forward portion of the bore E for admitting pressure fluid to the rearward end of the cylinder to impel the piston C forwardly. The extension D is provided with a reduced portion R so that when the piston approaches its rearward limiting position the front end of the passage Q will be uncovered to admit pressure fluid to the rearward end of the cylinder.

The admission of pressure fluid to the front end of the cylinder A is in this instance effected through a passage S leading from the front end of the cylinder to communicate with the bore E at a point rearwardly of the forward end of the passage Q. The passage S like the passage Q is also controlled by the extension D and is so positioned that at about the time the hammer piston delivers its blow to the anvil block J, pressure fluid will flow through the passage S into the front end of the cylinder for returning the piston.

95 In accordance with the practice of the invention a pair of lateral grip portions T and U are formed integrally with the back head to serve as a means for supporting the rock drill and for holding it to the work. The grip portion U is preferably of somewhat 100 smaller diameter than the opposed grip T to receive rotatably a handle sleeve V. The sleeve V has smooth unbroken outer perimetric surfaces and carries at its inner end face a cam W. By thus reducing the diameter of the grip portion U a shoulder X 105 will be formed at the juncture of the back head F and the grip U to form a stop for

limiting endwise movement of the sleeve V in one direction. Any suitable means may be provided for preventing accidental removal of the sleeve V from the grip U. A convenient means for accomplishing this is illustrated in the drawings in which a washer Y of substantially the same diameter as the sleeve abuts the outer end of the sleeve and is held in position by a bolt Z screwed into the end of the grip U.

The admission of pressure fluid conveyed to the back head F through the conduit L is controlled by a throttle valve b in the back head. The throttle valve b may be located in the same plane as the handle and is preferably arranged diagonally to the handle so that an extension c of the valve or, as illustrated in the present showing, a push rod d may extend at one end through the back head F to a point in line with the cam face W on the sleeve V. A spring e seated at one end on the valve b and with its other end against the connection O serves to normally hold the valve closed.

Suitable means are provided to limit the rotative movement of the sleeve V on the grip portion U. To that end faces f and g are formed longitudinally of the sleeve adjacent the ends of the cam face W. In the present instance the face f is adapted to contact with the side of the push rod d when the sleeve V is rotated to a position to permit the valve b to rest on its seat, and the face g is adapted to contact with the side of the push rod d only when the valve b is fully open. If desired, a flat face h may be formed at that end of the cam face W nearest the face g so that when the valve b has been opened to wide limits the sleeve V will be held against rotation by the action of the spring e.

In the operation of the device, whenever it is desired to admit pressure fluid into the cylinder A for reciprocating the piston C, the sleeve V may be rotated in a counter-clockwise direction as viewed from the right hand side of the figures. Such rotation of the sleeve will cause the cam surface W to ride on the outer end of the push rod d and will force the valve b from its seat. Continued rotation in this direction of the sleeve V will carry the flat surface h to contact with the end of the push rod d and the sleeve V may then be released by the operator and will be held securely against rotation by the pressure of the spring e.

The advantages of this invention reside chiefly in the fact that the perimetric surface of the grip portions T and U may remain substantially unbroken throughout their lengths. This construction renders these grip portions strong and eliminates the undue breakage thereof which frequently occurs in drills of this type. By means of the

controlling mechanism hereinbefore described the admission of pressure fluid to the rock drill may at all times be accurately and efficiently controlled. Another desirable advantage of this construction is that the operator may at all times apply full pressure to the handle of the drill with both hands without necessitating the frequent release of one of the grips, or a change of position of his hands, for the purpose of manipulating the pressure fluid controlling element.

I claim:

1. In a fluid actuated rock drill, the combination of a cylinder, a reciprocating hammer piston in the cylinder, a back head for the cylinder, grip portions on the back head forming a handle, a throttle valve in the back head for controlling the admission of pressure fluid to the cylinder, an extension on the valve, a rotatable handle sleeve on one of the grip portions said sleeve having smooth unbroken outer perimetric surfaces throughout its length, and a cam on the end face of the sleeve to abut the extension for opening and closing the valve.

2. In a fluid actuated rock drill, the combination of a cylinder, a reciprocating hammer piston in the cylinder, a back head for the cylinder, grip portions on the back head forming a handle, a throttle valve located transversely in the back head for controlling the admission of pressure fluid to the cylinder, an extension on the valve, a rotatable handle sleeve on one of the grip portions, a cam on the inner end face of the sleeve to abut the valve extension for opening and closing the valve, a shoulder on the back head to limit endwise movement of the sleeve in an inward direction, and a bolt in the handle to hold the sleeve against removal from the handle.

3. In a fluid actuated rock drill, the combination of a cylinder, a reciprocating hammer piston in the cylinder, a back head for the cylinder, lateral grip portions on the back head forming a handle for manipulating the rock drill, said grip portions having smooth unbroken perimetric surfaces, a throttle valve located diagonally in the back head for controlling the admission of pressure fluid to the cylinder, an extension on the valve extending through the back head into the handle, a sleeve rotatable on the handle, a cam on the inner end face of the sleeve to abut the valve extension for unseating the valve, a shoulder on the back head for limiting endwise movement of the sleeve in an inward direction, means for preventing removal of the sleeve from the handle, a spring for closing the valve upon release of the sleeve.

In testimony whereof I have signed this specification.

GORDON LEE.
